UNITED STATES PATENT OFFICE

ARMISTEAD R. LONG, OF SCARBRO, WEST VIRGINIA

MINE CAR

Application filed January 10, 1930. Serial No. 419,896.

This invention relates to improvements in industrial cars, such as mine cars and quarry cars but more particularly mine cars.

The primary object of the invention is the provision of an improved mine car having a unitary truck construction, with means for mounting a body thereon in such flexible relation that the wheels of the truck will ride efficiently over the tracks of a roadbed without warping the body or transmitting forces to the body which would be apt to cause destructive strains in the body.

A further object of this invention is the provision of an improved mine car having the body so constructed with respect to the supporting wheels and other parts of the truck that it is possible to place the floor line of the car much lower than in conventional mine cars, and place the body beams much closer to the hubs of the truck wheels than is usual, so that the coal or other article receiving capacity of the body may be made relatively large without the overall dimensions of the car exceeding what might be termed a standard maximum dimension.

A further object of this invention is the provision of improved means for mounting a mine car or other body upon a supporting chassis in such relation that the load will be supported in very close proximity to the supporting plane of the wheels.

A further object of this invention is the provision of an improved body bracing and reinforcing structure.

Other objects and advantages of this invention will be apparent during the course of the following detailed description.

In the accompanying drawings, forming a part of this specification, and wherein similar reference characters designate corresponding parts throughout the several views,

Figure 1 is a bottom plan view of the mine car, showing the unitary truck in its relation to the body of the car.

Figure 2 is a longitudinal sectional view taken through the improved mine car substantially along the center line thereof.

Figure 3 is a transverse sectional view taken substantially on the line 3—3 of Figure 1.

Figure 4 is a plan view of the unitary truck structure.

Figure 5 is a fragmentary sectional view taken through one of the devices which positively connects the body of the car to the unitary truck or chassis in a compensating relation, substantially on the line 5—5 of Figure 2.

Figure 6 is a sectional view taken substantially on the line 6—6 of Figure 1.

Figure 7 is a fragmentary perspective view of one corner of the chassis or unitary truck structure, showing the relation in which an end of an axle is associated with a side connecting beam.

Figure 8 is a fragmentary perspective view of an end of one of the truck axle connecting bars or beams.

Figure 9 is a sectional view taken substantially on the line 9—9 of Figure 5.

Figure 10 is a sectional view taken through one of the truck bodies reinforcing and connecting bracket devices, substantially on the line 10—10 of Figure 1.

Figure 11 is a fragmentary perspective view showing the relation of an improved bracket with respect to one of the main side beams of the car body.

Figure 12 is a sectional view taken substantially on the line 12—12 of Figure 3.

Figure 13 is a fragmentary end view of a modified axle structure which may be used as a part of the truck, in lieu of the one-piece axle shown in the other views.

Figure 14 is a perspective view showing an end of the main body of the axle with respect to its detached spindle, showing the relation of means to secure the spindle to the axle body.

In the drawings, wherein for the purpose of illustration is shown a preferred type of the mine car, with the details in preferred and modified arrangement, the letter A may generally designate the improved mine car, which may consist of a unitary truck or chassis B upon which the improved mine car body C may be compactly mounted in a compensating, flexible, and efficiently supported relation, for the transportation of maximum loads and quantities of materials.

Referring to the truck B, the same includes a pair of similarly constructed axles 15 and 16, each having wheels 46 rotatably mounted on the spindle ends thereof; the axles 15 and 16 being fixedly connected in unitary parallelism by means of parallel beams 18 and 19.

The axles 15 and 16 are of identical construction, each including a flat, relatively thin but wide body or tie bar portion 25, tapered or reduced laterally at its ends. The ends having integrally connected upwardly extending reinforcing and draft force receiving blocks or shanks 26, which are polygonal in cross section, and the lower surfaces of which are preferably flush with the bottom surface of the body 25. They are of generally square cross section, and the opposite side surfaces are parallel. They extend above the plane of the tie body portion 25 of their respective axles in preferably right angled relation, and have right angled plane surfaces at their inner or axle body facing surfaces. At their outer surfaces, the axle blocks 25 or extensions 26 are provided with spindles 30, projecting in any desired length, which may be of forged steel or other suitable bearing material. The axles 15 and 16, as described, are preferably of one-piece construction, drop-forged, and the extensions 26 are very sturdy, having ample strength for directly receiving the forces incidental to partial support of the load, and pulling of the loaded car. The main function of the body portion 25 is to provide means for stably mounting the truck, and connecting and tying together the spindles and the wheels thereof. It is to be noted that the spindles 30 are cylindrical in formation, and preferably located near the upper edges of the extensions 26, so that the latter have vertical surfaces 31 at their outer sides below the spindles. Parallel surfaces 32 are provided at the inner surfaces of the extensions 26.

The beams 18 and 19 are of identical construction, the same being of relatively great height compared to the thickness thereof, and in cross section preferably being rectangular. These beams, inwardly from their lower edges 35, are vertically slotted at 36 for receiving the block-shaped draft receiving portions 26 of the axles 15 and 16, in a tight fitting relation; the beams 18 and 19 straddling the supporting block portions 26 of the axles so that the outer faces of the beams 18 and 19 lie flush with the surfaces 31 of said block portions 26, as is clearly shown in Figure 3 of the drawings. Means are provided to permanently secure the beams 18 and 19 in a stable and accurate relation with respect to the axles, which consist in providing on each spindle 30 a reinforcing, retaining and load supporting plate or member 37, which is appreciably thicker than the beams 18 or 19; each of said plates preferably being of rec-

tangular appearance, although the corners thereof may be beveled if found desirable. These plates or members 37 are apertured at 38, and shrunk onto the spindles 30 with their inner sides abutting tightly and flush against the surfaces 31 of the axle offsets 26, as shown in Figure 3. The height of the plates 37 relative to the beams 18 and 19 is such that the top edges of the plates 37 and the adjacent beams 18 or 19 lie flush, and directly receive thereon the car body in a load supporting relation, as will be subsequently mentioned. The plates 37 are permanently affixed by shrinking upon the spindles 30 and the beams 18 and 19 are rigidly connected to said plates preferably by riveting, at 41. The beams may be welded to plates 37 if found more desirable. It is of course understood that the heads of the rivets 41 are countersunk, so that there are no projections at the inner sides of the beams or outer sides of the plates 37. Narrow ring-shaped collars 42 are also shrunk upon the spindles 30 of the axles, in immediate abutment against the outer sides of the plates 37; the diameter of the collars 42 being such that they will be snugly but detachably received within the inner socket passageways 44 of the inside hub extensions 45 of the wheels 46. The latter are conventional in nature, and are supported by means of anti-friction thrust bearings, upon the spindles 30, with the track engaging flanges 47 thereof lying as close as possible to the load supporting plates 37 and the beams 18 and 19. The proximity in which the wheels may be durably and efficiently mounted upon the ends of the axles with respect to the plates 37 and truck beams 18 and 19 is an important feature of the invention, and the hub extensions 45, of course, movably abut against the outer sides of the plates 37; the washers 42 serving to exclude foreign materials from the bearings within the wheels 46.

As seen from Figure 8, the beams 18 and 19 may be apertured at 41^a for receiving the rivets 41. Adjacent their ends, the beams 18 and 19 are formed with vertically elongated openings 50 adapted to receive suitable means shown in Figure 5, carried by the body of the mine car, to provide a positive yet compensating connection between the unitary truck and the body.

So far as the truck B is concerned, the above described construction fixedly connects the axles 15 and 16 in definite relation with respect to each other, and with respect to the beams 18 and 19. The latter are laterally flexible, or susceptible of bending or twisting without fracture or liability of permanent distortion. All parts of the truck are connected permanently together, except that the wheels are detachable from the spindle ends 30. This feature is conventional and need not be further described.

The body C is built so that it will snugly conform to the unitary truck structure, for the purpose of increasing the carrying capacity. It includes the main supporting 5 longitudinal beams 55 and 56, shown in Figure 1, which are Z-shaped in cross section, as is probably best shown in Figure 10 of the drawings; each of said beams including the vertically disposed web or body portion 57 having an upper outwardly extending flange 58 and a lower inwardly extending horizontal floor supporting flange 59. The beams 55 and 56 have a floor 60 connected with the inwardly flanged portions 59 preferably bolted thereto, at 61, as shown in Figure 10 of the drawings, although the marginal edges of the floor may be spot welded to the main beam flanges if desired. The bottom floor extensions 62 may be secured as by bolting or 10 welding to the top flanges 58 of the beams 55 and 56, extending outwardly therefrom for the purpose of giving the car body increased width. Upright walls 63 are provided at the outer margins of the floor extensions 62. These upright walls 63 may be of any approved height. At the ends of the car, suitable mine car bumper construction 64 may be provided, in a durably reinforced and connected relation with the ends of the 15 longitudinal beams 55 and 56, and with the floor and upright walls of the body of the car, as shown in the drawings, and as otherwise provided in my co-pending application, Serial No. 319,890. Of course, end walls 65 may be provided for the body, and an end gate 66 of any approved character may also be provided.

To properly support and reinforce the extension portions of the body beyond the 20 beams 55 and 56, suitable channel-shaped brackets 70 are provided, having top walls 71 and depending brace flanges 72. These parts are assembled as shown in Figures 10 and 11 of the drawings, and elsewhere, with 25 the walls 71 beneath the floor extensions 62 in contact therewith, and bolted thereto, as at 73. The inner ends of the walls 71 are cut out as at 74 to accommodate the flange 58 of the adjacent body beam 55 or 56, as the 30 case may be, in order that the inner edges 77 of the flanges 72 may abut against the outer surfaces of the webs or portions 57 of the beams 55 or 56. It is readily apparent that the vertically positioned brace flanges 55 35 72, due to their engagement against the beams 55 or 56 will support the floor extensions 62 in a cantilever fashion. To further reinforce, support, and maintain the bottom extensions and the body walls of the 40 car in position, a bracket reinforcing and connecting member 78 is employed in connection with the brackets 70, including a vertical portion 79 shown in Figure 10, abutting against the outer side of the web portion 57 of the body beam 55 or 56, and bolted thereto, at 80. The bracket 78 furthermore includes a horizontal reinforcing portion 81 extending beneath and connected with the flanges 58 and top walls 71, and being bolted with the latter, as by the bolts 73 45 above mentioned. The brackets 78 are bent upwardly at the outer ends of the portions 81 and extended at 82 along the outer sides of the side walls or upright walls 63 of the car body, being secured thereto as by welding, riveting, bolting, or in any other approved manner. Such arrangement effectively braces the lateral portions of the car body beyond the beams 55 and 56, and directly distributes the forces incident to load 50 directly onto the beams 55 and 56 of the body, from whence they are transmitted into the unitary truck in a relation to be subsequently mentioned.

For the application of the body C upon the unitary truck B, the former is provided with vertical slots or openings 85, extending upwardly from the bottom of the Z-bars or beams 55 and 56, at points directly opposite one another, for the movable accommodation 55 of the draft portions 26 of the axles 15 and 16. These openings 85 are arranged so that the block offsets 26 extend therethrough into the article receiving compartment or chamber of the truck body; caps 87 being riveted or otherwise secured at 88 to provide additional shoulders and surfaces which contact with the block portions 26 of the axles during a car pulling operation to better distribute the forces incident to draft, into the car body. 60 These caps also prevent dust, dirt, and foreign materials from passing through the openings 85 as an incident of relative movement of the axle portions therein. With respect to the truck, the portions 57 of the body beams 55 and 56 are so placed that when the body rests upon the axle, the outer surfaces of the beams will lie in close spaced relation with the inner surfaces of the beams 65 18 and 19 of the truck B, as shown in Figure 3. The spaces, designated at 90 in Figure 3, between these facing surfaces of the main beams of the truck and car body, are just sufficient to permit of the lateral tipping of the car body upon the truck, which it is intended shall occur to prevent eccentric strains in the car body as a result of travel of the truck over irregular tracks. The lower surfaces of the horizontal flange portions 58 of the beams 55 and 56 rest directly upon the 70 top edges of the truck beams 18 and 19 and the top edges of the truck beam reinforcing and load supporting plates or members 37, as shown in Figure 3 and elsewhere. It is thus quite obvious that the weight of the car body, empty or loaded, is transmitted partially through the truck beams 18 and 19 and mainly by the plates 37 into the spindles and portions 26 of the axles. The edges at the 75 tops of the slots 85 directly rest on the top 130

surfaces of the heavy portions 26 of the axles. The body portions 25 of the truck axles 15 and 16 extend beneath the floor 60 of the truck body; the latter resting thereon lightly, but it is quite obvious that the weight of the load in the truck is not supported on the body portions 25 of the axles with any shearing effect.

As will be seen from Figure 12 of the drawings, the slots 85 are of greater width than the widths of the offset portions 26 of the axles received therein; providing sufficient spacing to admit of quite limited free play of the axles in the openings 85, longitudinally of the car.

The mine car body C, for each axle of the truck B, is also provided with a pair of spaced angle cross beams 95, at the opposite sides of the body portion 25 of each of the axles 15 and 16, secured to the car beams 55 and 56, as by bolts 96, or the cross beams may be spot welded at these locations, or otherwise secured. The cross beams not only laterally brace the body B against buckling, but the spaced, depending vertical flanges 95^a thereof furnish guards to guide and assist in the retention of the axles of the truck in place with respect to the car body during relative movement between the car body and truck, as a result of passage of the car over irregular tracks. It is noted from Figure 12, that the longitudinal side edges of the body portions 25 of the axles are slightly spaced from their facing surfaces of the angles 95^a, to admit of the longitudinal play of the car body upon the truck, necessitated by reason of the compensating connection of the body upon the truck.

Referring to Figures 5, 6, 7 and 8 of the drawings, and elsewhere, it is noted that means are provided to positively connect the car body to the truck or chassis, yet to permit of the compensating movement between the body and truck. These means comprise a plurality of bolts 100, projecting through suitable openings in the vertical body portions 57 of the beams of the truck body; the head portions of the bolts lying within the body, and the screw threaded shanks 101 thereof extending transversely beyond the outer sides of the side beams of the body, and through the elongated openings 50 in the ends of the beams 18 and 19 of the truck. These bolts 100 are provided with rotatable sleeves 103 or rings 103 thereon, disposed within the planes of the respective openings 50, acting as rollers to facilitate movement between the truck and body parts without the usual wear and friction. The rollers 103 are each held in position by means of a nut 104 on the outer screw threaded end 101 of its bolt 100; washers 105 being held by these nuts against the outer ends of the rollers 103, adjacent the outer sides of the beams 18 and 19, as shown in Figure 5. The washers are sufficiently

large that they will not slip through the openings 50, but will retain the parts in the relation shown in Figure 5. The clearance between the outer periphery of the rollers or sleeves 103 at the opposite sides of the slots or openings 50 in which they operate, is preferably greater than the clearances which the axles have in their fittings in the openings 85 of the car body, due to the fact that there will be some angular deflection of the truck B off center with respect to the body C, at times, which may be considered as an essential feature of the compensating movement. When the body C rests upon the truck B in the arrangement above mentioned, shown in Figure 3, it is to be noted that the rollers 103 are positioned at the bottoms of their respective openings 50, so that no shearing or load support of the car is brought upon the bolt 100. The bolts have vertical play in the openings 50, as is quite apparent from Figure 6. Due to the fact that an essential characteristic of the invention is the increased carrying capacity of the car body, provision is made in the car body to accommodate portions of the wheels 46 of the truck, and to this end, as shown in Figure 3 and elsewhere, suitable openings 110 are cut in the floor extensions 62 of the car body, through which the upper portions of the wheels project; these openings 110 being closed by suitable segmental hoods 111, suitably bolted, welded, or otherwise secured to the adjacent floor and wall surfaces of the car body, to completely close off the openings 110 from the coal carrying compartment. It is to be noted from Figure 9 that there is sufficient clearance left in the caps 87 to permit the compensating play between the car body and truck in the relation mentioned. For economical reasons, and from the standpoint of manufacture, it may be desirable to make the spindle portions of the axle detachable from the other portions of the axle, in order that the former may be constructed of high grade steel or other material, and the latter may be cast or otherwise formed or constructed of cheaper materials. To this end, as shown in Figures 13 and 14, the modified axle F may be provided, including a flat relatively wide and thin tie bar body portion 115, which at the ends thereof is provided with vertical upwardly extending offset blocks 116, in a right angled relation therewith, which are relatively heavy and stocky, and provided with polygonal openings 117 transversely therethrough at a location above the top surface of the body 115. The spindle structures may each include a spindle portion 120, of solid form, or other shape if desired, having reduced outer ends 121, and inner integral portions 122 of polygonal cross section. These portions 122 are preferably square, and the openings 117 detachably receive the same therein, preferably with a driven fit. This holds the spindle 120 in proper relation to the

other portions of the axle, and a pin 124 may be employed for preventing detachment of the spindle portion of the axle from the offset block 116; the pin being extended through 5 suitable transverse passageways 125 provided in the portions 116 and 122 of the axle, in a relation which is perfectly apparent from Figures 13 and 14 of the drawings.

It is to be noted that the hub portion 45 10 of the truck wheel 46, in each instance, is very short and located very close to the plane of the wheel which rides on the rail. Because of the fact that the plates or members 37 are shrunk upon the axle spindles, they 15 really comprise part of the axle and extend normal to the axis of the spindle. They very securely reinforce the axle at the juncture of the spindles with the block portions 26 of the axles, and prevent any liability of bending 20 of the axle spindles where the latter join said block portions 26, as is quite apparent. The load is supported directly by the members 37 and transmitted to the spindles, the shear coming at approximately the planes 25 where the hub portions 45 of the wheels abut against the outer sides of the plates 37. There will be no bending of the spindles whatsoever, in view of the compacted placement of the plates 37 between the wheel hub 30 and the portions 26 of the axles. It is to be noted that the distance from the outer side of the plate 37 measured along the axis of the spindle to the plane where the wheel rides upon the rail is very short. This arrangement 35 increases the load carrying efficiency of the axle structure, without unnecessary addition to the bulk thereof. It is thus apparent that the weight of the car and its load is directed into the axle structure closer to 40 the rail than has been heretofore the practice.

When the truck is riding over irregularly aligned rails, the compensating movement between the car body and truck is enabled, without the transmission of destructive 45 strains to the car body, because the thin connecting beams 18 and 19 of the truck structure will flex with a slight twisting effect at locations somewhere near the midway point between the two axle structures of the truck.

50 Various changes in the shape, size, and arrangement of parts may be made to the form of invention herein shown and described, without departing from the spirit of the invention or the scope of the claims.

55 I claim:

1. In a mine car, the combination of a car body, a single unitary truck, means mounting the car body upon the single unitary truck with a compensating free floating connection, 60 and means permitting limited movement of the car body relative to the unitary truck in a direction longitudinally of the car.

65 2. A mine car structure comprising a car body, a truck including a plurality of axles having wheels at the ends of each, means con-

nnecting the axles together so that they will move in substantial unison, and means non-resiliently mounting the car body upon the truck in a limited free floating relation therewith. 70

3. In a car, the combination of a car body, a truck structure including an axle, the car body being directly supported upon the axle so that the latter has free floating action with respect thereto, wheels for the axle, and means 75 remote from the axle for positively connecting the car body with the truck for limited relative movement of the axle with respect to the body.

4. In car body supporting means, the combination of an axle including an elongated body portion having enlarged block-like portions rigid at the ends thereof, reduced spindles extending outwardly from said block portions in close axial parallelism with the 80 body portion, wheels rotatable on said spindles, and means on the block portions of the axles for direct transmission of draft forces thereto.

5. In means for supporting car bodies, the 85 combination of an axle having reduced spindles at the ends thereof with shoulders facing outwardly in the direction of said spindles, load supporting members fixedly secured to the spindles in abutment against 90 said shoulders and at the top thereof extending above the top surface of the axle for receiving a load.

6. In means for supporting car bodies, the 95 combination of an axle having reduced spindles at the ends thereof with shoulders facing outwardly in the direction of said spindles, load supporting members fixedly secured to the spindles in abutment against said shoulders and at the tops thereof extending 100 above the adjacent top surfaces of the axle, said axle between said members being vertically dropped to a plane below the axes of the spindles.

7. In a truck for industrial cars, the combination of a pair of supporting axles having 110 reduced spindles at the ends of each, the axles having abrupt shoulders facing outwardly in the direction of said spindles, load supporting and axle reinforcing members shrunk on said spindles in engagement against the shoulders of the axles, and beams connecting 115 said axles and longitudinally extended between similar ends of the axles for connecting the latter together in a unitary arrangement.

8. In a truck for industrial cars, the combination of a pair of supporting axles having 120 reduced spindles at the ends of each, the axles having abrupt shoulders facing outwardly in the direction of said spindles, load supporting and axle reinforcing members shrunk on said spindles in engagement against the shoulders of the axles, and beams connecting 125 said axles and longitudinally extended be- 130

tween similar ends of the axles for connecting the latter together in a unitary arrangement, said beams being relatively thin and having plane surfaces at their inner sides.

5 9. In a truck for industrial cars, the combination of a pair of supporting axles having reduced spindles at the ends of each, the axles having abrupt shoulders facing outwardly in the direction of said spindles, load supporting 10 and axle reinforcing members shrunk on said spindles in engagement against the shoulders of the axles, beams connecting said axles and longitudinally extended between similar ends of the axles for connecting the latter together 15 in a unitary arrangement, said beams being relatively thin and having plane surfaces at their inner sides, the axles at the beams where the latter rest thereon being heavily formed, and the axles between said heavily formed 20 portions being vertically dropped between said beams.

10. In an industrial car, the combination of a unitary truck including axles, wheels on each of the ends of each of the axles, and 25 means connecting the axles together in a fixedly spaced relation, and a car body mounted directly upon the axles of the truck with a limited floating connection.

11. In a car structure, the combination of 30 a truck including spaced axles having wheels at the ends thereof, and narrow bar-like beams supported upon the axles in close proximity to the wheels, reinforcing means connecting said beams to the axles at the location 35 where the beams are supported thereby, in a non-movable relation with said axles, and a car body resting upon the upper surfaces of said truck beams at the reinforcing means in supported relation thereby.

40 12. In a car structure, the combination of a truck including spaced axles having wheels at the ends thereof, narrow bar-like beams supported upon the axles in close proximity to the wheels, reinforcing means connecting said beams to the axles at the locations where 45 the beams are associated therewith in a non-movable relation with said axles, a car body resting upon the upper surfaces of said truck beams at the reinforcing means in supported 50 relation thereby, the car body extending downwardly along and slightly spaced from the inner sides of said beams and resting upon the beams in a relatively movable relation therewith.

55 13. In a car structure, the combination of a truck including spaced axles having wheels at the ends thereof, narrow bar-like beams supported upon the axles in close proximity to the wheels, reinforcing means connecting said beams to the axles at the location where 60 the beams are associated therewith, in a non-movable relation with said axles, a car body resting upon the upper surfaces of said truck beams at the reinforcing means in supported 65 relation thereby, the car body extending

downwardly along and slightly spaced from the inner sides of said beams and resting upon the beams in a relatively movable relation therewith, and means connecting the car body positively with the beams with a loose connection permitting relative vertical movement of the car body upon said beams. 70

14. In a car, the combination of a construction including spaced axles, wheels on the axles, and longitudinal side flat bar beams connecting the axles at similar ends immediately adjacent the inner sides of said wheels, and a car body including beams mounted on the upper edges of said truck beams and including compartment providing portions extending downwardly between the beams of the truck and outwardly over the wheels of the truck. 75

15. In a car, the combination of a construction including spaced axles, wheels on the axles, longitudinal side flat bar beams connecting the axles at similar ends immediately adjacent the inner sides of said wheels, a car body including beams mounted on the upper edges of said truck beams and including compartment providing portions extending downwardly between the beams of the truck and outwardly over the wheels of the truck, and means connecting the car body in 80 said relation to the axles of the truck with a limited floating connection. 85

16. In a car truck, the combination of spaced axles, wheels rotatable at the outer ends of the axles, the axles at the inner sides of the wheels being formed to receive shearing action of a load thereon and having heavy portions, longitudinal side beams connecting similar ends of the axles each formed with vertical slots extending upwardly from the bottom edges thereof receiving the heavy portions of the axles therein, and reinforcing and load supporting members fixedly secured on the axles and surrounding said axles adjacent said heavy portions and rigidly attached with said beams. 100

17. In a car, the combination of a truck structure including supporting beams rigid therewith, a car body mounted on the truck structure with a free floating connection, said beams having vertically elongated openings therein, and means connected with the car body extending into the openings of the beams and movable therein to limit the extent to which the car body may move relative to the truck. 115

18. In a car, the combination of a truck structure including supporting beams rigid therewith, a car body mounted on the truck structure with a free floating connection, said beams having vertically elongated openings therein, means connected with the car body extending into the openings of the beams and movable therein to limit the extent to which the car body may move relative to the truck, 120

5 said last mentioned means including bolts fixedly carried by the car body extending through the openings of the beams, anti-friction rollers on the bolts adapted to engage the walls of said openings, and nuts and washers on the bolts preventing dislocation of the rollers from within said openings.

10 19. In a car body, the combination of longitudinal Z-beams each including vertical web or body portions, upper outwardly extending flanges and lower inwardly extending flanges, car floor portions mounted on the lower inwardly extending flanges, extension car floor portions mounted on the 15 upper outwardly extending flanges and extending laterally outwardly from said beams, the car body below the upper outwardly extending flanges of said beams being unobstructed, said beams having slots extending 20 upwardly through the lower flanges and partially through the web of the beams, a truck structure including spaced axles, narrow flat bar beams connecting similar ends of the axles, means reinforcing the bar beams adjacent 25 the points at which they engage the axles, wheels on said axles, the outwardly extending flanges of the car body beams resting on the top edges of the beams of the truck with portions of the axles adjacent the wheels 30 30 non-rotatably received in the slots of the car body beams, the car body resting in said relation on the axles in a vertically floating relation with respect to the truck.

35 20. In a car body of the class described, the combination of spaced longitudinal main beams, a bottom connected with the lower ends of the beams, extension floors connected with the upper ends of the beams and extending laterally outwardly, inverted channel braces secured to said extension floors and having vertical brace flange portions normal to the extension floors and in abutment at their inner ends against the main beams, the car body having upright side walls at the 40 outer margins of the extension floors, and bracing members located between the flanges of the channel members and attached to the main beams, means connecting each bracing member last mentioned to the channel braces and to the extension floor, said bracing member having portions extending upwardly exteriorly of the upright side walls and secured therewith.

45 21. As an article of manufacture a car axle comprising a main body and a detachable spindle, the main body having upright load supporting extensions at the ends thereof transversely apertured in the line of the 50 axles, said apertures being of polygonal cross section, the spindle being of higher grade material than the main body of the axle and having a non-rotatable polygonal end force-fitted into the opening of the upright extension of the axle body, and means positively 55

securing said axle in the relation mentioned in the opening of said extension.

22. In a car truck the combination of an axle having heavy draft portions with a light connecting portion therebetween, said heavy draft portions having reduced spindles extending outwardly normal thereto so that shoulders are provided on the heavier portions facing outwardly in the direction of said spindles, load supporting plates rigidly affixed on said spindles in surface abutment with said shoulders, and wheels rotatably mounted on said spindles including short hubs at the inner sides thereof in sliding abutment with the outer sides of said load supporting plates. 70 75 80

23. In a car truck, the combination of a truck comprising a pair of axles, each of said axles including heavy draft receiving portions with a relatively light connecting body, 85 said draft receiving portions at the outer sides thereof having reduced spindles with shoulders at the juncture where said spindles extend therefrom, load supporting plates rigidly affixed on said spindles in surface abutment with said shoulders, wheels rotatably mounted on said spindles including short hubs at the inner sides thereof in sliding abutment with the outer sides of said load supporting plates, and thin flexible connecting beams fixedly secured with the draft receiving portions of said axles at similar ends of the axles in rigidly affixed relation with the load supporting plates adjacent thereto. 90 95

24. In a car, the combination of a truck structure including a laterally flexible frame and track engaging wheels at opposite ends thereof, a car body, and means mounting the car body upon the truck structure so that the truck frame may be laterally flexed without imparting flexure stresses to the car body. 100 105

25. In a car the combination of a truck structure including a laterally flexible frame and track engaging wheels at opposite ends thereof, a car body, and means mounting the car body upon the truck structure and connected therewith for limited relative movement vertically and longitudinally with respect to the truck structure so that the truck frame may flex without imparting flexure stresses to the car body. 110 115

26. In a mine car, the combination of a car body, a single unitary truck, means mounting the car body upon the single unitary truck with a compensating free floating action, and means connecting the car body upon the truck for limited relative movement vertically and longitudinally with respect to the truck. 120 125

27. In a car, the combination of a truck structure including supporting beams rigidly therewith, a car body mounted on the truck structure with a free floating connection, said beams having vertically elongated openings 130

transversely therethrough, and horizontal bolts carried by the car body releasably extending into the elongated openings of the beams and movable therein vertically and horizontally to limit the extent to which the car body may move relative to the truck.
